UNITED STATES PATENT OFFICE.

WILLIAM F. BOSSERT, OF UTICA, NEW YORK, ASSIGNOR TO THE BOSSERT ELECTRIC CONSTRUCTION COMPANY, OF UTICA, NEW YORK.

PLUG-FUSE BOARD.

No. 802,553.

Specification of Letters Patent.

Patented Oct. 24, 1905.

Application filed February 14, 1905. Serial No. 245,637.

To all whom it may concern:

Be it known that I, WILLIAM F. BOSSERT, residing at Utica, in the county of Oneida and State of New York, have invented certain Improvements in Plug-Fuse Boards, of which the following is a specification.

The invention about to be described has reference to plug-fuse panels or boards of the variety shown in Patent No. 738,519, granted to me September 8, 1903, upon which the present application is an improvement and has especial reference to the plug-fuse holders which are provided with the branch bus-bars from the main bus-bars in such boards.

Commonly the plug-fuse holders are made from metals of rather high resistance, as brass castings, and are interposed in and are attached to the branch bus-bars; but I have found that such brass devices are of very much greater resistance than sheet metals—as, for instance, copper—and are also much more costly, as extra work is required in filing and smoothing the same in order that they shall present a finished appearance. In carrying out my invention I form the said holders preferably from heavy sheet-copper by first stamping out a blank and then drawing or pressing the same into the required shape by passing the blank through a progressive series of dies and forming therein a threaded nut to receive the ordinary commercial fuse-plug and drilling holes for screws and bolts.

The invention also relates to the combination of such an improved fuse-holder with the bus-bars, the branch bus-bars, and the supporting-base of a panel or board, as I will now proceed to describe, and point out in the appended claims.

Of the drawings which form a part of and illustrate the invention, Figure 1 is a plan view of a base panel or board with one of the fuse-plugs omitted from a holder. Fig. 2 is an elevation of the same, one of the fuse-holders being represented in section on line xx of Fig. 1. Figs. 3, 4, and 5 are to represent the method of stamping out and drawing or pressing the fuse-holder from sheet, Fig. 3 being a plan view of a blank, Fig. 4 an elevation of the same, and Fig. 5 an elevation of a holder as it leaves the last dies.

In the drawings, a represents a slab of marble or slate forming the insulating base

or support for the respective parts of the panel or board, and 1 and 2 are hollow posts 55 to which the leading-in conductors may be connected, which are secured to the base a by the bolts 6, 6, also passing through the bus-bars 9 and 7, respectively. The bus-bar 7 is connected to the branch bus-bar 4 by the 60 screw 8, while the bus-bar 9 is elevated to pass over the bar 4 and connects with the branch bus-bar 3 by the screw 10, provided with the nut 11. The parallel branch bus-bars 3 and 4 are preferably of unequal length 65 and are secured to the base a by the bolts 13 at each end thereof, having a flat head 12, upon the top of the bars. The bolt 13 extends through the base a and is provided with a nut 27, by means of which the head 12 is 70 drawn down hard upon the bars 3 and 4. The heads 12 of the bolts constitute a contact-surface, as will be explained hereinafter, for the fuse-plug.

The fuse-plug holder A is formed preferably from sheet-copper of the proper thickness, and a blank similar to that shown in Figs. 3 and 4, A^3 , is stamped therefrom. A hole b is punched at one end and a tubular portion c turned down. The blank has an 80 enlarged part e and a tang d , and by subsequent operations the enlarged portion e is hollowed or sunken, as e^2 , and its edges turned up at substantially right angles, as ff , leaving the ring part h and the tang or 85 foot d in two different and parallel planes, and then a coarse thread g is formed on the inner surface of the tubular portion c and holes are drilled for the holding-bolts in the foot. When thus formed, the fuse-holder 90 is finished on an emery-wheel or in any other suitable manner and is ready for use. When the enlarged or intermediate portion e is sunken, as described, and the edges ff turned up, a very strong support is formed, as the 95 said edges give a bracing and stiffening effect, and the ring h is enabled to withstand the thrust put upon it when the fuse-plug B is screwed down hard onto the contact-head 12; but at the same time, since the holder is 100 attached to the base at only one side and constructed as described, it is sufficiently resilient to "give" or yield, so as to avoid liability of damage resulting from screwing the fuse-plug B down too hard on the head 12. 105

produced when the fuse-wire is deflagrated, it can be readily renewed and another put in its place without throwing away the bus-bar.

The fuse-holder A is placed upon the base 5 in such a position that the center of the opening b is over the center of the contact-head 12, and each holder is secured to the base by the screw 14 and the bolt 17. The bolt 17 is provided with a knurled nut 16 and serves as 10 a binder to connect branching conductors to the holder.

B represents the common fuse-plug having a porcelain body insulating a metal screw-threaded sleeve *j* and contacting tip 15 *i*, between which is placed the fuse-wire, and when in the fuse-holder A the sleeve *j* makes connection with the ring *h* and the tip *i* with the bolt-head 12, and thus continues the circuit from the branch bus-bar to the binding-screw 17; but when the fuse has been deflagrated the circuit is interrupted and an air-gap formed between the bolt-head 12 and the ring *h* of the fuse-holder in a manner well 20 understood.

25 I claim as my invention—

1. A fuse-plug holder consisting of a holder portion, an intermediate portion, and a single foot portion, all of said portions being in-

tegral and made from sheet metal, the foot portion being provided with holes, the intermediate portion being provided with strengthening means, and the holder portion being 30 perforated and internally threaded.

2. A fuse-plug holder stamped from sheet metal and having one end perforated and 35 threaded and the opposite end formed with a foot having bolt-holes, the said ends being in parallel planes, and joined by an intermediate portion centrally hollowed or sunken to form supporting edges or sides. 40

3. A fuse-plug holder stamped from sheet metal and having one end perforated and a tubular portion turned down and internally threaded, the opposite end being formed as a foot having bolt-holes, the said ends being in 45 parallel planes connected by an intermediate curved portion having its edges or sides bent at substantially right angles.

In testimony whereof I have signed my name to this specification, in the presence of 50 two subscribing witnesses, this 10th day of February, 1905.

WILLIAM F. BOSSERT.
